UNITED STATES PATENT OFFICE.

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

RECTANGULAR SLIDE VALVE FOR ROCK DRILLS.

Application filed May 20, 1925. Serial No. 31,485.

This invention relates to fluid actuated rock drills, but more particularly to an improved distributing valve construction in the form of a rectangular slide valve for controlling only the inlet to both ends of the cylinder, a free exhaust being controlled by the piston.

The objects of the invention are to secure a simple quick acting slide valve of the current thrown type which may be conveniently located at one side of the cylinder and provided with a flat valve box having a rectangular chamber.

Further objects of the invention will hereinafter appear and the invention is shown in one of its preferred forms in the accompanying drawings, in which—

Figure 1 is a longitudinal sectional elevation of so much of a rock drill as will serve to illustrate the invention,

Figure 2 is a view similar to Figure 1 showing the piston and valve in a different position,

Figure 3 is a horizontal sectional plan view partly broken away taken on the line 3—3 of Figure 1 through the valve looking in the direction of the arrows, and

Figure 4 is a detail side elevation of the valve.

Referring to the drawings, the cylinder A is provided with the reciprocating piston B in this instance having a fluted forward extension C. In the particular rod drill illustrated, automatic rifle bar rotation is provided for the drill steel (not shown) and the rifle bar is indicated at D.

The cylinder is provided with the centrally located free exhaust port E controlled only by the piston. Inlet ports F and G for the ends of the cylinder communicate with the rectangular recess H forming a valve chamber in the valve box J into which the rectangular valve K is adapted to be inserted from the side, provision being afforded to permit the valve to slide back and forth between the end walls L and O of said valve chamber which form stops and seats for the valve.

Live pressure fluid is supplied at the inlet P and controlled by the throttle valve Q in the valve box cover R and passes through and around one side or the other of the valve to the ends of the cylinder according to the position of the valve.

The valve K is in the form of a rectan-

gular block of appreciably greater length than width or height, as indicated in Figures 3 and 4, and the valve seats on its longer sides. The valve is provided with flanges S at each side formed with openings T to permit the pressure fluid to pass. The valve is also formed with a hollow central portion, in this instance, two central apertures U being shown through the valve web V so that the pressure fluid may pass through the valve itself and through the apertures T in both flanges at one side of the valve. The combined cross sectional area of the openings T in the flanges at one side of the valve is less than the throat area of the restricted portions W of the cylinder inlet passages X communicating with the cylinder inlet ports F and G so that the current of live pressure fluid tending to pass through the flange openings T as the pressure in the passage X is reduced aids in moving the valve.

In the operation of the device, let it be assumed that the piston and valve are in the positions indicated in Figure 1 in which the piston is starting on its forward stroke. In such positions the live pressure fluid from the supply P passes to the valve chamber H and from thence through the flange openings T to the inlet port F for the rear end of the cylinder for driving the piston forwardly. Until the piston uncovers the exhaust port E the valve will be subject to pressure due to the fact that live pressure fluid is present within the valve chamber H, the inlet port F and the rearward end of the cylinder. As soon as the exhaust port E is uncovered by the piston C there is a drop in pressure within the cylinder and the inlet port F, but no substantial drop in pressure in the valve chamber H itself, this unbalanced condition being accentuated by the fact that the cross sectional area of the openings T in the flange is less than the throat area of the portion W of the port F, as previously stated. This unbalanced condition of the valve, taken in conjunction with the presence of air trapped in the forward end of the cylinder and acting upon the opposite end face of the valve through the passage G, will shift the valve to the position shown in Figure 2, closing off the supply of pressure fluid to the rearward end of the cylinder and admitting pressure fluid to the forward end of the cylinder for driving the piston rearwardly.

Owing to the fact that the valve is of rectangular shape the seating surfaces on the longer sides of the valve have a longer length than if the valve was circular or of the spool type having substantially the same total valve surface area subjected to pressure. For this reason the valve may have a materially less travel for the same opening obtained for the spool valve, which adds to the efficiency of the valve since the minimum travel possible with a given valve opening is highly desirable.

I claim:

A fluid actuated rock drill, comprising a cylinder and reciprocating piston, a free exhaust port located centrally of the cylinder

and controlled only by the piston, a valve box having a rectangular chamber, a distributing valve in the form of a rectangular block slideable in said valve box, said valve having flanges at each end provided with openings for the passage of live pressure fluid, cylinder inlet passages in the valve chest, the combined cross sectional area of the openings in the flanges being less than the throat area of the said cylinder inlet passages in the valve chest adjacent the valve, and inlet ports for the ends of the cylinder controlled only by said valve.

In testimony whereof I have signed this specification.

CHARLES C. HANSEN.
